UNITED STATES PATENT OFFICE

EVER EVERSON, OF HATTIESBURG, MISSISSIPPI

CUPBOARD

Application filed August 14, 1931. Serial No. 557,177.

This invention relates to cupboards and similar storage receptacles and has for its object the provision of means whereby a large number of articles may be stored in a small space and will be readily accessible when necessary. The invention seeks to provide a cupboard which may be disposed in the corner of a room or compartment and which will be rotatably mounted so that any desired storage space within the cupboard may be brought within reach easily and quickly. The invention also seeks to provide means whereby the cupboard will be normally held stationary, and also to provide means whereby access of ants and other insects to the cupboard will be prevented. The invention is illustrated in the accompanying drawing and consists in certain novel features which will be hereinafter first fully described and then more particularly defined in the claim.

In the drawing,

Figure 1 is a top plan view of a cupboard embodying the invention,

Fig. 2 is a vertical section on the line 2—2 of Fig. 1, and

Fig. 3 is a horizontal section on the line 3—3 of Fig. 2.

In carrying out the invention, there is provided a cup or pan 1 which is secured upon the floor of a room at a point adjacent a corner thereof, and rising from the bottom of this pan is a step bearing 2 receiving the lower end of a post 3 which may be extended to any desired height. About the upper end of the post or shaft is mounted a split bearing ring or collar 4 which closely encircles the post or shaft and is provided with terminal lugs 5 through which a securing bolt 6 is inserted whereby the bearing may be caused to exert a desired degree of friction upon the post or shaft so that the rotation of the shaft will be retarded and it will be normally held stationary. The bearing 4 is also provided with radial lugs 6 at diametrically opposite points, and these lugs receive the threaded ends 7 of brace rods 8 which extend divergently toward the meeting side walls of the room. Lock nuts 9 are mounted upon the threaded terminals 7 at opposite sides of the

lugs 6 so that they may be turned home against the lugs and thereby firmly secure the braces in place. At their ends remote from the post or shaft 3, the braces 8 are formed into eyes 10 which fit over pins 11 rising from bearings 12 provided on the bottoms of cups or pans 13 which are secured to the respective walls of the room and may contain liquid or powder, so that any insects which may reach the pans will be destroyed and prevented from traveling along the braces to the post and thence finding access to the cupboard. It will also be understood that the cup or pan 1 is intended to contain liquid or other insect destroyer, as indicated at 14.

Secured to the post or shaft 3 and radiating therefrom are partitions or wings 15 which extend to a cylindrical shell or casing 16, said casing being provided with an imperforate top 17 and a bottom 18, preferably circular in form, as shown and as will be understood. The cylindrical shell or casing, with its top and bottom, forms the outer body of the cupboard and is equipped with openings 19 at various points in its area to provide access to the interior, each opening being normally covered and closed by a door 20 of any approved form, as will be understood. Upon the sides of each partition 15 are secured cleats 21, and shelves 22 rest on and are supported by said cleats, the shelves being of a general triangular form, as shown in Fig. 3, whereby they will fit readily and closely within the compartments of the cupboard and may be easily inserted or removed to facilitate cleaning.

To facilitate replenishment of the liquid within the cup or pan 1, an opening, indicated at 23, is provided in the bottom 18 adjacent the post or shaft 3 so that, by reaching into the cupboard, a supply of liquid may be readily poured through said opening into the pan.

From the foregoing description, it will be seen that I have provided an exceedingly simple cupboard whereby a large number of articles may be stored within a small compass, and space in the corner of a room which is now ordinarily wasted may be advan-

tageously utilized. The friction exerted upon the upper end of the central post or shaft by the split bearing will hold the cupboard normally against rotation but will yield readily to slight force exerted on the cupboard, so that when it is desired to remove or insert an article, the cupboard may be readily turned to bring the desired compartment within reach. The cupboard is thoroughly braced so that its turning movement will be steady and it cannot be shifted accidentally from its proper position.

Having thus described the invention, I claim:

A cupboard comprising a cylindrical casing, shelves within the casing, a shaft concentric to the casing and carrying the casing and the shelves, a pan below the casing, a bearing cup rising centrally from the pan and receiving the lower end of the shaft, a split collar encircling the upper end of the shaft, means for effecting frictional engagement between the collar and the shaft, lugs on opposite sides of the collar, cups, means for supporting said cups in angular spaced relation to each other and the upper end of the shaft, pins rising from said cups, braces each secured at one end in a lug on the split collar and having its opposite end provided with an eye engaged over the respective pin.

In testimony whereof I affix my signature.

EVER EVERSON. [L. s.]
